IMPACT DEVICE

Lewis K. Davis, Hampton, N. J.

Application September 23, 1931, Serial No. 564,491

6 Claims. (Cl. 140—113)

This invention relates to an impact press and has particular reference to a press whose motive power is obtained by the expansion of gases of combustion within a confined space.

5 The general principle of producing power by means of rapidly expanding gases of combustion has been utilized heretofore for various purposes, but unless the rate of expansion of the gases is controlled in some way to insure complete combustion of the material before utilizing the force thus generated, the maximum power of the gas expansion is not obtained, for the reason that the resistance to movement of the object to be moved is usually relatively low as compared to 10 initial power provided by the partial combustion of the material, so that the reserve power of the remaining unburned material is dissipated in the enlarged space provided by the premature movement of the object.

20 It is the principal object of this invention to provide a device in which the expansion of gases produced by the rapid combustion of a highly combustible material is retarded a sufficient time to permit of complete combustion of the material 25 whereby the full power of the expanding gases may be utilized to do a greatly increased amount of work.

This object is obtained in a preferred embodiment of the invention in which a cartridge of 30 gunpowder or the like is detonated in a cylinder containing a piston, whose movement is retarded by novel means until the powder is completely burned and the resultant gas pressure exceeds a limit determined by the retarding means. More 35 particularly, the retarding means comprises a bar or rod of metal or the like which is sheared off by the piston only when the gas pressure builds up to a pressure such that the shearing resistance of the rod or bar is exceeded. Thus, the 40 impact of the piston caused by the sudden release thereof by the shearing of the rod or bar is utilized to do useful work such as punching, die-pressing or forming metals, pressing two or more members together, or the like, and the frame 45 of the device is arranged for receiving dies of different shapes, punches of different sizes and shapes and the like for cooperation with the piston.

By changing the density or character of the 50 powder in the cartridges and providing bars or rods of different shear resistances, any degree of controlled power or force may be obtained with the new device of this invention, depending upon requirements.

55 It will be seen that the new impact press of

this invention is compact and readily operated without the use of outside power, and requires only a supply of powder cartridges and shear rods for procuring repeated operations of the device. Accordingly, the device may be used in 5 outlying districts where power is not readily obtainable and is also admirably adapted as a portable source of power.

For a better understanding of the invention, reference is made to the accompanying drawing, 10 in which

Fig. 1 is a longitudinal section through the new press as seen along line 1—1 of Fig. 2;

Fig. 2 is a longitudinal section through the new press as seen along the line 2—2 of Fig. 1; 15

Fig. 3 is a transverse cross-section through the cartridge firing mechanism as seen along the line 3—3 of Fig. 2;

Fig. 4 is a transverse cross-section through the cylinder and piston as seen along the line 4—4 20 of Fig. 1, and

Fig. 5 is a transverse cross-section through the die holder as seen along the line 5—5 of Fig. 1.

In the drawing, numeral 10 designates the frame of the press which is supported on four 25 feet 11 and is provided with a die or other tool chamber 12 at the base with which communicates the lower end of the power cylinder 10' extending upwardly from the frame 10.

The head of the cylinder 10' is provided with 30 a lateral recess 13 in which is removably mounted a block 14 having a pin 15 extending laterally through the head of the cylinder 10' and having a notch 17 which is normally engaged by one end of a latch 16. This latch 16 is pivoted on a 35 stud 18 screwed into the side of the head of cylinder 10'.

Slidably mounted in an axial passage through the block 14 is a firing pin 19 which is normally urged in a downward direction by a coil spring 40 20 seated between a collar 19' on the firing pin 19 and the cap 21 threaded on the upper end of block 14. The firing pin 19 is normally held in retracted position by the locking pin 22' which is inserted through a suitable opening in the firing pin 19 and overlies the cap 21. In this way the spring is compressed in readiness for advancing the firing pin 19 when it is released by withdrawing locking pin 22'. A handle 22 on the firing pin 19 may be pulled outwardly to retract 50 the firing pin and for the purpose of inserting the locking pin 22' to hold the firing pin 19 in retracted position. Any other equivalent trigger or firing pin release mechanism may be employed with equal facility.

The upper end of the cylinder 10' is closed gas tightly by a plug or cartridge clip 23 having an axial passage for the reception of the cartridge 25 containing gunpowder, or the like. The percussion cap 26 of the cartridge 25 lies in alignment with the tip 27 of the firing pin 19 so as to be struck and detonated thereby when the pin is released. The cartridge clip or plug 23 may be exposed for removing empty cartridge shells and replacing them with unfired cartridges by removing block 14. This may be done by releasing latch 16 and withdrawing the block from the recess 13 in the head of the cylinder 10'. It will be observed in the section of Figs. 1 and 2 and in cross-section of the block illustrated in Fig. 3 that the head of cylinder 10' is formed with flanges 13' which overlap the block 14 so that it is locked against the recoil shock produced by the firing of cartridge 25.

Slidably mounted in the bore of cylinder 10' is a piston 28 whose upper end lies adjacent the lower or discharge end of the cartridge 25 when the piston lies in the raised position illustrated in Figs. 1 and 2. The lower end of this piston 28 is provided with an enlarged hammer 29 having side grooves adapted to receive the keys or guides 30 on the frame 10. Passing laterally through the piston 28 is a hardened steel bushing 31, which is adapted to align with similar hardened steel bushings 32 and 33 inserted in the opposite side walls of frame 10 when the piston 28 and its hammer 29 are raised into the position shown in Figs. 1 and 2. The piston 28 and its hammer 29 may be so raised by means of suitable levers or the like inserted in recesses 34 in the sides of the hammer 29. The adjacent ends of the bushings 31, 32 and 33 are shaped to form cooperating shear blades 32' and 33' as illustrated in Fig. 2.

Inserted jointly through bushings 31, 32 and 33, so as to hold the piston 28 and its hammer 29 in raised position, is a rod 35 of tough metal or the like having a predetermined resistance to shearing by the shear blades 32' and 33'. Secured to the ends of a small shaft 36 journaled in frame 10 are a pair of clips 37 and 38, clip 38 being provided with a lateral handle 39, whereby both clips may be raised from their normal position in which their free ends cover the open ends of bushings 32 and 33. The stop pin 38' locates these clips 37 and 38 in this normal position in which they hold in place the shear rod 35. When it is desired to remove the severed pieces of the sheared rod and replace it with a new rod, it is only necessary to grasp handle 39 to move clips 37 and 38 to expose the openings in bushings 33 and 32 respectively.

Located in the bottom of the die opening 12 of frame 10 is a combination anvil and die 40, whose lower edge is provided with a groove through which passes the bolt 41, this bolt acting as a key for centering the anvil die 40 and also serving to clamp it securely in the frame by drawing together the two sides of the frame as the bolt 40 is tightened.

Slidably mounted in the opening of the frame and centered and guided by the keys 30 is the upper die 42 which cooperates with the lower die 40 in the usual way. These dies 40 and 42 may be shaped to produce any kind of forming operation, punching operation, shearing operation, or the like. For example, as shown in the drawing, the dies 40 and 42 are shaped to embrace a sheath 43 which is adapted to be clamped around the cable 44. Although the dies are shaped in

this way to perform this cable sheathing function, they may obviously be arranged and adapted to perform any other function, or they may be substituted by other mechanical elements which are designed to produce work in accordance with the power which is applied thereto. In order to remove these dies the lower one, 40, is raised to clear the bolt 41 and may then be withdrawn, while the upper die 42 then drops down to clear keys or guides 30 and may also be withdrawn.

In operation, the piston 28 and hammer 29 are raised by inserting a lever or rod in recesses 34 in the hammer 29 and a shearing pin or rod 35 is inserted through aligned bushings 31, 32 and 33 in order to hold the piston 28 and hammer 29 in this elevated position. Then the clips 37 and 38 are moved downwardly to stop 38' by handle 39 to close the open ends of bushings 32 and 33, so that the shear rod 35 is held in position.

The block 14 is removed from the frame 10 after being unlatched by releasing latch 16, and cartridge 25, containing a charge of gunpowder or other highly inflammable or explosive material producing a large volume of expanding gas when ignited, is inserted in the cartridge clip 23. Firing pin 19 is retracted by pulling upwardly on the handle 22, and is locked in place by inserting locking pin 22' in the manner described. The firing mechanism in block 14 is replaced in frame 10 and locked in position by latch 16 in readiness for operation.

The dies or other forming parts or tools 40 and 42 are arranged in position to clamp the cable 44 or perform any other operation.

The withdrawal of pin 22' releases firing pin 19 so that spring 20 forces firing pin tip 27 against the cap 26 of cartridge 25 to fire the same. The rapidly expanding gases of combustion of the powder in cartridge 25 tend to force the piston 28 downwardly at once, but the piston is retarded by shear rod 35, until the gas pressure is sufficient to cause the shear blades 32' and 33' to cut relatively slowly through the shear pin 35. This retardation enables the powder to burn completely so that the gases of combustion have full time to exert their greatest force before being released. Accordingly, when blades 32' and 33' finally sever the shear pin 35 the hammer 29 is released suddenly and is forced downwardly into contact with die 42 with a considerable impact, so that the sheath 43 is instantly clamped around the cable 44 through the cooperation of dies 40 and 42.

It will be seen that the use of the shear rod 35 prevents premature movement of the hammer 29 in response to the initial expansion of the partially burned powder, and allows sufficient time for complete combustion so that the expanding gases exert their greatest accumulated force upon the piston 28 before the hammer 29 is released to strike the dies 42. The relatively slow shear of the rod 35 allows the gas to expand slightly and thus its power is increased before it is released. Thus by this arrangement a greatly augmented power is procured for forcing the two dies 42 and 40 together.

By providing shear rods 35 of different shearing resistances, the time of powder combustion and gas expansion may be increased or decreased within limits in accordance with operating requirements. Also, by arranging the density or character of the powder charge in cartridge 25, the speed of powder combustion may be arranged

to suit all requirements of operation. For example, by increasing the charge in cartridge 25 and providing a rod 35 having a high shear modulus a practically unlimited amount of power may be obtained in a simple fashion and without requiring large or extensive equipment or the use of outside power.

This invention may therefore be used in outlying districts or other places where power is not obtainable, or in such localities where standardized jobs of forming, shearing, punching or the like are done occasionally, and the like. The only supplies necessary to operate the device of this invention comprise a number of cartridges 25 of the same or different strengths, and a corresponding number of shear rods 35 of the same or different shear resistances. Thus, simply by replacing the cartridges 25 as exploded and rods 35 as sheared, the device may be employed any number of times without requiring the use of extensive power equipment or other outside power supply. Also the device may be set up in a short time and operated instantaneously and readily and any number of times and is readily portable.

25 I claim:

1. In an impact press, the combination of a frame, a piston slidable therein, means for receiving a charge of combustible material for generating gas to act on said piston and move the same, and shearable means on the frame engaging the piston for resisting movement thereof, said means being arranged to be sheared by said piston at a predetermined gas pressure.

2. In an impact press, the combination of a frame, a piston slidable therein, means for receiving a charge of combustible material for generating gas to act on said piston and move the same, and a shearable member extending between the frame and the piston for resisting relative movement between them, said member being arranged to be sheared at a predetermined gas pressure.

3. In an impact press, the combination of a frame, a piston slidable therein, means for receiving a charge of combustible material for generating gas to act on said piston and move the same, shearing blades between said piston and said frame, and a shearable member cooperating with said blades for severance thereby at a predetermined gas pressure.

4. In an impact press, the combination of a frame, a piston slidable therein, means for receiving a charge of combustible material for generating gas to act on said piston and move the same, said piston and frame having aligned apertures, and a shearable member in the apertures for severance by movement by said piston under 15 a predetermined gas pressure.

5. In an impact press, the combination of a frame, a piston slidable therein, means for receiving a charge of combustible material for generating gas to act on said piston and move the same, said piston and frame having aligned apertures, a shearable member in the apertures for retarding movement of said piston, and shearing blades between said piston and frame cooperating with said member for severance thereby at a 25 predetermined gas pressure.

6. In an impact press, the combination of a frame having a cylinder, a piston slidable therein, a hammer on the piston, means in the frame for cooperation with said hammer, means for receiving a replaceable cartridge of combustible material arranged to discharge gas into said cylinder and having a detonating cap, firing mechanism mounted on said frame for detonating the cap of said cartridge, said mechanism being movable 35 to expose said cartridge, a shearable member extending between said piston and said frame, and blades between said piston and frame for shearing said member at a predetermined gas pressure to release said hammer for impact with said first 40 means.

LEWIS K. DAVIS.
